(57) **CLAIM**

The ornamental design for a graduation shot glass, as shown and described.

DESCRIPTION

FIG. 1 is a perspective view of a graduation shot glass showing my new design;

FIG. 2 is a front view thereof;

FIG. 3 is a right side view thereof;

FIG. 4 is a left side view thereof;

FIG. 5 is a rear view thereof;

FIG. 6 is a bottom plan view thereof;

FIG. 7 is a top plan view thereof;

FIG. 8 is a perspective view showing a second embodiment of the graduation shot glass; and,

FIG. 9 is a perspective view showing a third embodiment of the graduation shot glass of my new design.

The broken lines in the drawings are for illustrative purposes only and form no part of the claimed design.
